United States Patent Office

Des. 202,824
Patented Nov. 9, 1965

202,824

BOTTLE

Jerome Gould, Encino, Calif., assignor to Armour and Company, Chicago, Ill., a corporation of Delaware

Filed Dec. 4, 1964, Ser. No. 82,914

Term of patent 14 years

(Cl. D58—8)

FIG. 1 is a front elevational view of a bottle showing my new design;

FIG. 2 is a side elevational view thereof;

FIG. 3 is a top plan view thereof;

FIG. 4 is a bottom plan view thereof.

The rear and side not shown are the same as the front and side respectively shown.

I claim:

The ornamental design for a bottle, substantially as shown and described.
